Burney & Co., of same place,

Letter Patent No. 2183-Dated Oct. 10-1865.

Design for the Stock of a Cistern or Well Pump.

The schedule referred to in these Letters Patent and making part of the same.

Whom it may concern:

Bethel Brown, that of Leonard Egerton, of the Village of Seneca Falls, in the County of Seneca, and State of New York, since invented or produced a new and original design for the stock or body of a cistern or well pump, and do hereby declare that the following is a full and exact description of the same:

The pump is made of cast iron or other suitable metal and except the peculiarity of my design in the usual form. The peculiar form of a portion of the stock and the sections in which it is apparently divided by projecting mouldings and the form and combination of those sections, constitute the design which I claim as my original invention, as shown in the accompanying drawings forming a part of this specification to which reference is made. Figure 1 is the design for a well pump of which the portion A, B represents the stock or body divided into nearly equal sections by the projecting mouldings d, d, d. The sections c, e, are cylindrical in form and near the upper ends thereof, but by a sloping cut starting near the upper end and going to a change to a decagon presenting ten flat sides. The angle in line with the cylindrical portion, the sloping cut to the upper ends gives the resemblance of consecutive arches extending around these sections. The sections

successive arches extending around that section. The sections
of the cylindrical uniform. The section, from which the
spout projects is swelled outward in a curve to form the bend
perpendicular section of which will present an outline similar to
that produced by the cross section of the egg, mentioned above.

together on their flat bottom will clearly appear by inspection of
said drawing.

What I claim as new and any original design and
invention is

The design for a pump as shown and described.
